[57] CLAIM

The ornamental design for a cover for a VCR tape slot, as shown and described.

DESCRIPTION

FIG. 1 is a top, front and end perspective view of the cover for a cover for a VCR tape slot showing our new design;

FIG. 2 is a left end elevational view thereof, the right end being a mirror image of the left end shown in FIG. 2;

FIG. 3 is a front elevational view thereof;

FIG. 4 is a rear elevational view thereof; and,

FIG. 5 is a top plan view thereof, the bottom view being a mirror image of the top view shown in FIG. 5.

FIG. 1

FIG. 2

FIG. 3

FIG. 4

FIG. 5
